United States Patent

Des. 240,705
Patented July 27, 1976

240,705

ABRADER

Hans Franzen, Vendelso, and Johnny Lind, Alvsjo,
Sweden, assignors to Sandvik Aktiebolag, Sandviken,
Sweden

Filed May 23, 1975, Ser. No. 580,225

Term of patent 14 years

Int. Cl. D8—05

U.S. Cl. D8—90

Fig. 1.

Fig. 2.

Fig. 4.

Fig. 3

FIG. 1 is a side elevational view of an abrader of the invention;

FIG. 2 is a bottom plan view of the abrader;

FIG. 3 is an end view of the abrader as seen from the handle end of the abrader; and

FIG. 4 is an end view of the abrader as seen from the end remote from the handle.

We claim:

The ornamental design for an abrader, as shown and described.
